Patented Dec. 5, 1922.

FIG. 1.

FIG. 2.

Inventor.
Tom J. Barger,
by Robert W. Denner,
Attorney.

UNITED STATES PATENT OFFICE.

TOM J. BARGER, OF OILTON, OKLAHOMA.

OIL-WELL PUMP.

Application filed April 17, 1922. Serial No. 553,406.

To all whom it may concern:

Be it known that I, TOM J. BARGER, a citizen of the United States, residing at Oilton, in the county of Creek and State of

5 Oklahoma, have invented certain new and useful Improvements in Oil-Well Pumps, of which the following is a specification.

This invention relates to pumps, for oil wells and other similar wells, which are 10 provided with sand traps; and it consists in the novel construction and combination of the parts hereinafter fully described and claimed, which enable the foot valve to be raised and lowered in the sand trap for 15 repair, without disturbing the suction pipe.

In the drawings, Figure 1 is a vertical section through a portion of a pump provided with improvements according to this invention. Fig. 2 is a cross-section, taken on the 20 line 2—2 in Fig. 1.

The barrel 4 of the pump is provided with a slidable plunger 5 having a longitudinal passage for the liquid. This plunger and all parts above it are of any approved construction. The barrel 4 is secured to a collar 7, and a sand trap 8 is secured to a tubular extension 27 on the lower part of the collar. This extension has a bell-mouthed or conical portion 28 which is considerably 25 larger in area than the pump barrel.

The sand trap 8 is a cylindrical vessel of any desired length, and its lower end is closed by a tubular plug 9 which is screwed into the lower end portion of the sand trap. 35 The plug 9 has the usual socket 10 at its lower part, and is connected to the lower section of the suction pipe and to the tubing 11 in the usual way.

A foot valve 15 is arranged in a cage 16 having a long tubular stem 17. The valve cage has lateral openings 26 above the valve, and the tubular stem is supported in a guide 18 arranged in the sand trap and provided with radial spacing ribs 19 which hold it 45 centrally in the sand trap.

The upper section 14 of the suction pipe is screwed into the plug 9 at its lower end, and its upper end portion is screwed into an internal enlargement 29 at the lower end to 50 the tubular guide 18. The enlargement 29 is

smaller in diameter than the guide 18, and a shoulder 30 is formed at its upper end which supports the tubular stem 17 of the foot valve.

The tubular stem 17 is provided with a 55 circumferential groove 20, and 21 is packing material, such as leather, secured in the said groove. The packing is preferably retained in place by a short sleeve 31 which is screwed on the lower end portion of the stem and 60 which forms the bottom end of its circumferential groove.

The sand is discharged laterally into the conical or bell-mouthed lower part 28 of the extension 27, and falls by gravity into the 65 sand trap, and the liquid passes upwardly in the usual way through the plunger.

The foot valve and its stem can be removed and replaced without disturbing the suction pipe 14, as often as necessary, and 70 the bell-mouthed or conical part 28 enables the stem 17 to be raised without any risk of injury to the soft packing by contact with any angular projections or shoulders.

What I claim is:

1. A pump barrel, a sand trap having its upper end secured to the pump barrel, means for closing the lower end of the sand trap, a suction pipe secured in the lower part of the sand trap, a tubular guide secured to the 80 upper end portion of the said suction pipe and arranged in the sand trap, and a foot valve provided with a tubular stem having packing material which is slidable in the said tubular guide and is supported therein 85 independently of the said suction pipe.

2. A pump barrel, a sand trap having its upper end secured to the pump barrel, means for closing the lower end of the sand trap, a suction pipe secured in the lower part of 90 the sand trap, a tubular guide arranged in the sand trap and having an inwardly projecting enlargement at its lower part which is secured to the upper end portion of the suction pipe and which forms a shoulder in 95 the guide, and a foot valve provided with a tubular stem which is slidable in the said guide and which is supported by the said shoulder.

3. A pump barrel, a collar secured to the 100

pump barrel and having an internally bell-mouthed extension at its lower part, a sand trap secured over the said extension, means for closing the lower end of the sand trap, a suction pipe secured in the lower part of the sand trap, a tubular guide secured to the upper part of the suction pipe, and a foot

valve provided with a tubular stem having packing material which is slidable in the said tubular guide and is supported therein independently of the said suction pipe.

In testimony whereof I have affixed my signature.

TOM J. BARGER.
